I. BARNETT

WALL BRACKET FOR LIGHTING FIXTURES

Filed July 5, 1924

ISIDOR BARNETT
Inventor

By his Attorney
Max A. Goldstein

UNITED STATES PATENT OFFICE.

ISIDOR BARNETT, OF NEW YORK, N. Y.

DESIGN FOR A WALL BRACKET FOR LIGHTING FIXTURES.

Application filed July 5, 1924. Serial No. 10,069. Term of patent 3½ years.

To all whom it may concern:

Be it known that ISIDOR BARNETT, citizen of the United States, and resident of the city of New York, in the county of Kings and State of New York, has invented a new, original, and ornamental Design for Wall Brackets for Lighting Fixtures, of which the following is a specification, reference being had to the accompanying drawing, forming part thereof, in which,

The figure is a front elevational view of a wall bracket for lighting fixtures embodying my new design.

I claim:

The ornamental design for a wall bracket for lighting fixtures as shown.

Signed at New York city, this 30th day of June 1924.
